UNITED STATES PATENT OFFICE.

GIDEON M. GORDON, OF KANSAS CITY, MISSOURI.

DESIGN FOR A COFFEE CAN OR BIN.

SPECIFICATION forming part of Design No. 31,134, dated July 4, 1899.

Application filed April 10, 1899. Serial No. 712,557. Term of patent 14 years.

To all whom it may concern:

- Be it known that I, GIDEON M. GORDON, a citizen of the United States, residing at Kansas City, in the county of Jackson and State of Missouri, have invented and produced a new and original Design for Coffee Cans or Bins, of which the following is a specification, reference being had to the accompanying drawings, forming part thereof.
- 10 My invention relates to a new and useful design for coffee cans or bins; and it consists in certain features of configuration and surface ornamentation which are hereinafter pointed out.
- 15 In the accompanying drawings, illustrating the design, Figure 1 is a perspective view, and Fig. 2 a cross-section.
- The leading features of the design comprise a rectangular box having a gable-roof or top, 20 the surface of the roof being ornamented to represent shingles, while the body of the can or bin is ornamented to represent logs, brick-work, a door, and windows, the whole presenting to the eye a picture of a log-cabin.
- 25 Other features of the invention are representations of coon-skins fastened to the logs and a sign-board above the door.

Minor features of the design are as follows: A series of boards at one side of the brick-work, representing a chimney, boards below one of the windows, and a chair standing apparently just inside the cabin-door.

Referring to the drawings in detail, 1 represents the bottom, 2 the ends, 3 the front, 35 3^a the back, and 4 the gable-roof or top, of the can or bin.

The front sides and the ends of the can or

bin are ornamented to represent the longitudinal and transversely-extending logs 5 and 6, respectively, the ends of said logs showing 40 at the corners of the can or bin, as shown at 7. About centrally of the ornamented side is a door 8, apparently ajar, and apparently within the cabin is a chair 9. Apparently nailed to the logs at opposite sides of the door 45 are coon-skins 10, and above the door is a sign-board 11, apparently nailed in position. At one side of the door and below said sign-board is a window 12, one of its glass panes 50 apparently broken. At the opposite side of the door is a smaller window 13, with one of its panes also broken, the hole apparently being stopped up by a piece of fabric or paper 14. The cabin-wall is apparently patched below said window by the short planks or 55 boards 15.

At the exposed end of the can or bin is apparently a brick or stone chimney 16, having its upper portion of less width than its lower portion. To the right of said chimney is a 60 window 17 and to the left apparently a patch-work of short planks or boards 18.

The roof or top is ornamented to represent shingles, as shown at 19.

What I claim is—

65 The design for a coffee can or bin, substantially as herein shown and described.

In testimony whereof I affix my signature in the presence of two witnesses.

GIDEON M. GORDON.
